UNITED STATES PATENT OFFICE.

JUSTUS B. ENTZ, OF PHILADELPHIA, PENNSYLVANIA.

CANAL-BOAT PROPULSION.

SPECIFICATION forming part of Letters Patent No. 658,892, dated October 2, 1900.

Application filed February 10, 1900. Serial No. 4,734. (No model.)

To all whom it may concern:

Be it known that I, JUSTUS B. ENTZ, a citizen of the United States, residing in Philadelphia, county of Philadelphia, State of Pennsylvania, have invented certain new and useful Improvements in Canal-Boat Propulsion, of which the following is a specification, reference being had to the accompanying drawings, forming a part hereof.

10 In the transportation of freight over inland waterways it is usually the case that the same craft or vessel traverses both artificial waterways or canals and natural waterways, such as lakes and rivers. In artificial waterways 15 the use of a propeller on a canal-boat is undesirable because of the effect upon the banks of the canal of the wash produced by the propeller. Therefore it is usual to have canal-boats of the ordinary character taken in tow 20 by towboats when they reach a natural waterway. It is obvious that there are objections to this system and that on some accounts it would be advantageous to permit the towboat, or at least a self-propelled freight-carrier, to pass through the artificial waterway. 25 There are also objections to the present system of towing canal-boats through the artificial waterways.

It is the object of this invention to overcome 30 the objections above alluded to and make it possible for a vessel which carries its own source of motive power to be towed through an artificial waterway without the use of a propeller and to be driven through a natural 35 waterway by a propeller. To this end a vessel having a propeller and adapted for passage through both artificial and natural waterways is provided with a prime mover, an electric generator, and means for coupling and 40 uncoupling the prime mover to and from either the propeller or the electric generator at will, the generator being electrically connected with a motor mounted upon and driving a dirigible tractor adapted to run upon 45 the canal-bank and with which the vessel is mechanically connected when the vessel is in the artificial waterway or canal.

The invention will be further explained hereinafter with reference to the accompanying 50 drawings, in which—

Figure 1 is a view in side elevation, representing a canal-boat equipped with the prime

mover, a propeller, and an electric generator and connected both electrically and mechanically with an electric dirigible tractor on the 55 canal-bank; and Fig. 2 is a plan view thereof.

The vessel B may be of any suitable size and character, according to its intended use as a towboat alone, or a freight-carrier, or as both combined. It is provided with a suitable propeller C, an ordinary electric generator D, and a suitable prime mover E—such, for example, as a gas-engine—the said prime mover being capable of being coupled or uncoupled at will to or from the propeller or the electric 65 generator by means of suitable independent coupling devices, (represented, respectively, at C' and at D'.) The tractor F may be an electric locomotive of any suitable character, having an electric motor (represented at G) and 70 by preference a suitable controller, (represented at H.) The vessel is mechanically connected with the tractor when in the canal by a suitable tow-line I, and circuit connections (indicated at K) are then provided between 75 the generator D and the motor G, a switch k being included in such circuit connections on the vessel for use in emergencies.

No attempt has been made to illustrate details of construction in any respect, since all 80 of such details may be of any usual or preferred kind or form. It will be understood that while the vessel is in the canal the prime mover is coupled to the electric generator and the current generated is transmitted to 85 the motor which drives the tractor, the vessel being then mechanically connected to the tractor. When the vessel reaches a natural waterway the tractor is disconnected, both electrically and mechanically, and the prime 90 mover is uncoupled from the electric generator and coupled to the propeller.

I claim as my invention—

1. The combination with a vessel adapted to traverse artificial and natural waterways 95 and to be connected mechanically to a land-tractor, of a propeller, an electric generator adapted to be connected electrically with the motor of said tractor, a prime mover, and means to couple said prime mover to or from said propeller or said generator at will.

2. The combination with a vessel adapted to traverse artificial and natural waterways, a dirigible, electric land-tractor, and a me-

chanical connection from said vessel to said tractor, of a propeller for said vessel, an electric generator on the vessel and adapted to be connected electrically with the motor of
5 said tractor, a prime mover, and means to couple said prime mover to or from said propeller or said generator at will.

This specification signed and witnessed this
6th day of February, A. D. 1900.

JUSTUS B. ENTZ.

In presence of—
J. A. BRADLEY,
FRANKLIN T. KALAS.
